UNITED STATES PATENT OFFICE

108,494

DESIGN FOR EMBROIDERED NET

Alex Grossman, Jersey City, N. J., and Ellis Axelrod, Brooklyn, N. Y.

Application January 17, 1938, Serial No. 74,366

Term of patent 3½ years

To whom it may concern:

Be it known that we, Alex Grossman and Ellis Axelrod, both citizens of the United States, and residing at Jersey City, Hudson County, New Jersey, and Brooklyn, Kings County, New York, respectively, have invented a new, original, and ornamental Design for Embroidered Net, of which the following is a specification, reference being had to the accompanying drawing, forming part thereof, wherein—

The figure is a plan view of embroidered net showing our new design, with a unit of design outlined in dot and dash lines.

We claim:

The ornamental design for embroidered net substantially as shown and described.

ALEX GROSSMAN.
ELLIS AXELROD.
